UNITED STATES PATENT OFFICE.

JAMES M. MELLIS, OF VICTORIA, BRITISH COLUMBIA, AND WILLIAM H. L. MELLIS, OF PETERBORO, ONTARIO, CANADA.

DIRECTION INDICATOR.

Application filed November 4, 1924. Serial No. 747,831.

To all whom it may concern:

Be it known that we, JAMES M. MELLIS and WILLIAM H. L. MELLIS, citizens of the Dominion of Canada, residing, respectively, at Victoria, in the Province of British Columbia, and at Peterboro, in the Province of Ontario, have jointly invented certain new and useful Improvements in Direction Indicators, of which the following is a specification.

This invention relates to a direction indicator for self-propelled vehicles and is particularly designed to correspond with the hand signals as required by traffic ordinances in a positive, simple and direct manner.

It is an improvement on the device set forth by applicant in Patent No. 1,445,530 granted on the 13th February 1923.

The invention is fully set forth in the following specification, reference being made to the drawings by which it is accompanied, in which:

Fig. 1 is an elevation from the back of the signal proper and its mounting on the vehicle.

Fig. 2 is a plan of the same.

Fig. 3 is an enlarged detail in section of the mechanism by which the hand semaphore is connected to the operating mechanism and the electric lighting contact of the same.

Fig. 4 is an elevation from the position of the driver of the operative mechanism of the signal, the cover plate being removed. (This and the two following figures are to a larger scale than Figs. 1 and 2).

Fig. 5 is a vertical elevation and part section of the same, and

Fig. 6 is a plan of the clamp shown in Fig. 5 by which the operative mechanism is secured to the steering post or other position convenient for the driver.

In these drawings 2 represents the semaphore which, as in the patent previously referred to, is made in the shape of a hand and is hollow and divided into two parts in the plane of the hand to provide accommodation within for an incandescent lamp.

Spaces 3 are left in the joint of the two halves and in the separation of the fingers through which spaces the light may pass to more effectively display the conformation.

The front and back of the hand have each a glazed aperture 4 through which the light

is also displayed, that in the front being white or clear frosted glass to avoid glare, and in the back is coloured red to indicate to a following vehicle the driver's intent to turn or to stop.

One half of the hand is fixed to the hub 5 and the other half is removably secured by a dowel pin in the hub and a screw 6 in the outer end of the hand.

The hub 5 is secured by a set screw or other suitable means on a pivot 7 which is mounted to be turnable in the outer end of a bifurcated supporting arm 8, 9 having at the other end a clamp 10 by which it may be secured to the frame of the windshield or other convenient part to project outward from the side of the vehicle and to carry the semaphore 2 that it may move in a vertical plane.

On the end of this pivot shaft 7 within a casing 11 forming a part of the support 9 and closable with a cover 12, is secured a sheave 13 around which a flexible wire cable 14 is passed and secured at 15 to the sheave in any approved manner.

After passing once around the sheave 13 the ends of the flexible line 14 are passed through a flexible metallic tube 16 by which they are conducted to a reel 17 mounted to turn on a stud 18 in a casing 19 secured by a clamp 20 to the steering post of the vehicle or other position convenient for the driver.

After being passed around this reel 17 each end of the cable is made fast to a pin 21 on which the cable may be wound after being passed through a hole in the rim of the reel, see Fig. 4. By this means the cable may be tightened and adjusted to move the semaphore to the desired position in relation to the movement of a handle 22 secured to the rim of the reel 17 to project radially from it through the casing 19.

The hand 2 may be thus, by movement of the handle 22, be moved from its normal position between the supports 8 and 9 to the position indicated by the dot and dash line 23 in Fig. 1, to indicate an intent to turn to the right or to the position in which it is drawn in Figs. 1 and 2, indicating an intention to turn to the left, or it may be turned angularly downward to the position of the line 24 indicating an intent to stop.

The handle 22 may be provided with a spring detent which at the desired inter-

mediate positions will spring into one of the grooves 25 in the arc of the casing 19, so that the semaphore will be checked at the correct position.

- 5 To audibly intimate a driver's intention to turn or stop, the electric circuit 26 of the horn of the vehicle is introduced into the flexible tube 16 intermediate its ends and is conducted through it to the casing 19 of the 10 operating mechanism and is there connected to a terminal contact 27 on a suitable insulation and on the same insulation is a flexible contact 28 which extends across the contact 27. On the reel 17 is a pin 29, which, 15 when the reel is moved to indicate a signal, will engage the flexible contact 28 and press it into engagement with the terminal 27, thereby closing the circuit in which is the mechanism of the horn, so that any movement to give any signal is preceded with the 20 sounding of the horn.

Similarly, the lighting system of the car is connected to a wire 30 which passes through the flexible tube 16 to the casing 11 25 of the semaphore support and is there connected on suitable insulation to a resilient contact 32 which projects over the face of the sheave 13 and into contact with a metal disc 33 secured on suitable insulation to the 30 face of the sheave 13 and connected in any suitable manner to the socket for the lamp in the hub 5 of the hand, see Fig. 3.

From this disc 33 an arcuate segment 34 is removed from that side of it which is 35 toward the hand, so that when the hand is in its normal position, the resilient contact 32 will rest on the insulation and the circuit is open, but when the semaphore moves from the normal position to indicate any 40 desired turn or stop, the light circuit is closed by the contact 32 on the disc 33 and the hand is illuminated.

Both wires 16 and 30 are insulated and enclosed in a metallic sheathing so as to

prevent the insulation being injured by the 45 friction of the cables 14 in the flexible tubes 16.

The signal is positively operated by direct manual effort and is a mechanical substitute for the hand of the driver for which the 50 traffic rules have been devised, and which this mechanical means is designed to substitute.

The device can be readily applied to any 55 existing car without removal or alteration of any existing parts and without skilled assistance.

Attention is drawn to the facility afforded for access to any of the parts: To the incandescent lamp in the hand 2, or within 60 the casing 11 or 19, for attention to the tightening or adjustment of the cables 14, or the contact terminals of the horn sounding of lighting circuits, access to which can be attained by the removal of only one 65 screw for each.

Having now particularly described our invention, we hereby declare that what we claim as new and desire to be protected in by Letters Patent, is:

70 A direction indicator of the class described, comprising a bracket having parallel arms with horizontal bearing apertures at one end, and a clamping device at the other end for securing the bracket to a 75 windshield, a semaphore carrying shaft journaled in said apertures with the semaphore located between the arms, one of said arms having a chamber with a cap plate, a sheave in said chamber on said shaft, and 80 means passing through said chamber and associated with said sheave and to operate with said semaphore.

70 In testimony whereof we affix our signatures.

JAMES M. MELLIS.
WILLIAM H. L. MELLIS.
